UNITED STATES PATENT OFFICE.

WALTER S. RODGERS, OF DEMING, NEW MEXICO.

ROOF-SQUARE.

1,190,013.

Specification of Letters Patent.

Patented July 4, 1916.

Application filed January 15, 1915. Serial No. 2,392.

To all whom it may concern:

Be it known that I, WALTER S. RODGERS, a citizen of the United States, residing at Deming, in the county of Luna and State of New Mexico, have invented certain new and useful Improvements in Roof-Squares; and I do hereby declare the following to be a full, clear, and exact description of the invention, such as will enable others skilled in the art to which it appertains to make and use the same.

This invention relates to roof squares, and one of the principal objects of the invention is to provide a device of simple construction which can be quickly set for marking the cuts to be made on rafters of any pitch of roof, and in which the various elements may be folded inward to provide a small tool which will occupy but little space.

Another object of the invention is to provide a roof square which can be quickly adjusted for marking the right and left without changing the adjustment of the blades, and to provide a device in which a hip-roof can be laid off and the rafters marked for cutting the three angles without adjusting the tool for the different cuts.

These and other objects may be attained by means of the construction illustrated in the accompanying drawings, in which,

Figure 1 is a side elevation of a roof square made in accordance with this invention, Fig. 2 is a bottom plan view of the same with the blades adjusted for marking right and left rafters, Fig. 3 is a plan view of one of the try-square blades, Fig. 4 is a side elevation with the try-square blade extending at an angle to the handle member, Fig. 5 is a vertical sectional view through the tool taken on the line 5—5 of Fig. 1 looking in the direction indicated by the arrow, and Fig. 6 is a plan view of one of the try-square members removed from the tool.

Referring to the drawings, the numeral 1 designates a handle member, and secured in said member is a plate doubled upon itself at 2 near both ends, and secured within the handle by suitable rivets 3, one at each end. The plate is cut out in the central portion as at 4 to leave room for the hand to grasp the handle member 1. This plate is formed of two spaced members 5, and said members are bent outwardly at right angles as shown at 6 to provide oppositely directed longitudinal flanges 6. The opposite ends of the flanges 6 are enlarged, as indicated at 7, and

pivotal secured to pairs of arms or blades 8. The blades 8 are each provided with a longitudinal slot 9, the longitudinal edges of the slots being beveled as shown at 10 to 60 provide means whereby the heads 11 of the adjusting screws 12 will lie flush with the under face of the blade 8. Wing nuts 13 are fitted to the screws 12.

Pivotal connected at opposite ends of 65 the tool upon screws 15 are the arms or blades 16 and 17, said blades being disposed between the two spaced members 5, said screws 15 being provided with nuts 18. The blades 16 and 17 are each provided with a 70 longitudinal slot 19, by means of which the blades may be folded between the members 5 or extended at any desired angle thereto and held in an adjusted position by tightening the screws 15. The blade 17 is provided 75 with a branch slot 20 and the blade 16 is also provided with a similar branch slot 21.

In practice, the device is to be employed for measuring and cutting the oblique ends of roof beams, in which operation the arms 80 or blades 16 and 17 are adjusted for cutting the end of the beam on the desired angle to accord with the pitch of the roof. To mark the beam, the blades or arms 16 and 17 are laid flat against the rafter or beam and the 85 edge of the latter is engaged by one of the flanges 6. In making miter cuts the blades or arms 8 are properly adjusted and secured in position by the thumb nuts 13 and screws 12, it being understood that due to the position of two pairs of blades 8 the device may be reversed for cutting out opposite similar angles of the rafters or beams.

In operation, this device is employed for 95 properly marking the oblique ends of the roof beams, the blades 17 being for the purpose of measuring the angle to be cut at one end of the roof beam, on the portion adjacent the hip of the roof. It is of course apparent that the blade 16 is used in a similar 100 manner for measuring the angle to be cut from the beam forming the opposite side of the roof. After the blades have been properly adjusted by means of the slot 19 and the set screw 15 the instrument is placed with 105 the member 6 against one end of the beam to be cut, the blades 16 or 17 according to the angle, lying with the upper surface of the beam. The instrument is now ready to make the correct marking. In making the 110 miter cuts the miter blades 8 are brought into play and will be readily adjusted to the

desired angle to accord with the cut effected, by loosening the nuts 11 and moving the arms inwardly or outwardly as the case may be.

5 Various changes may be made in the details of construction without departing from the spirit and scope of the invention as defined in the claims.

What is claimed is:—

- 10 1. A roof square comprising a handle, supporting members spaced apart and connected to the handle, said supporting members having angular portions, blades pivotally and adjustably mounted on said angular portions, and blades mounted between said supporting members and provided with longitudinal slots and screws for holding the last mentioned blades in adjusted position.
- 15 2. A roof square comprising a handle, sup-

porting members connected to the handle 20 and spaced apart, said supporting members having outwardly directed portions, blades provided with longitudinal slots pivotally and adjustably mounted on said outwardly directed portions at opposite ends of the tool, 25 and a second set of blades each pivotally and adjustably connected between the spaced supporting members, whereby the right and left rafters for a roof may be marked for cutting without adjustment after the tool has been 30 set.

In testimony whereof I affix my signature in presence of two witnesses.

WALTER S. RODGERS.
